CLEANING DEVICE FOR GILL-BOX FALLERS

Harry Whitaker, South Barre, Mass.

Application June 26, 1934, Serial No. 732,491

1 Claim. (Cl. 19—129)

This invention relates to gill-boxes used in the preparation of wool for spinning. In the operation of such machines it is found that dirt and other waste material accumulates quite rapidly on the fallers and needles, so that it is necessary to stop each gill-box two or three or more times each working week for cleaning purposes. Furthermore, the manual removal, cleaning and replacement of a set of fallers involves a considerable expenditure of time and labor and the loss in machine production is substantial.

It is the object of my invention to provide improved means by which the lower fallers and needles in a gill-box may be automatically cleaned as the machine continues to operate, so that lost time due to the cleaning of fallers is very largely eliminated.

My invention further relates to arrangements and combinations of parts which will be herein-after described and more particularly pointed out in the appended claim.

A preferred form of the invention is shown in the drawing, in which

Fig. 1 is a diagrammatic sectional side elevation of a gill-box having my invention embodied therein;

Fig. 2 is a plan view of certain parts, looking in the direction of the arrow 2 in Fig. 1;

Fig. 3 is an enlarged partial plan view of a cleaning brush;

Fig. 4 is a sectional side elevation, taken along the line 4—4 in Fig. 3, and

Fig. 5 is a rear view, looking in the direction of the arrow 5 in Fig. 4.

Referring particularly to Figs. 1 and 2, I have shown portions of a gill-box of the intersecting type, in which upper and lower sets of fallers are used.

The gill-box comprises front or feed rolls 10, a stationary guide 11, a series of upper fallers 12, a series of lower fallers 14, back or delivery rolls 15, and a guide or trumpet 16 through which the sliver S is delivered to press rolls 17 and a receiving can 18. An apron or conveyor 19 runs over the lower back or delivery roll 15.

The fallers 12 and 14 are progressively advanced toward the delivery rolls 15 by gill-screws 20 and 21 (Fig. 2). After completing their travel toward the delivery rolls 15, the upper fallers are raised and the lower fallers are lowered to secondary gill screws (not shown) which are of steeper pitch and return the fallers toward the feed rolls 10 as indicated by the arrow a in Fig. 1.

After completing their return travel, the upper fallers are lowered and the lower fallers are raised

to a position in which they will be raised and be turned to a position in which they will be cleaned and cleaned with an adjustment of the gill-screws 20 and 21. The fallers 14 are caused to move upwardly and the lower fallers 14 are caused to move downwardly, so that the fallers 14 will be cleaned by the brush B. The fallers 14 are caused to move upwardly and the lower fallers 14 are caused to move downwardly, so that the fallers 14 will be cleaned by the brush B.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

The brush B is located in the gill-box so that it will be engaged by the fallers 14 as they move upwardly and will be cleaned by the fallers 14 as they move downwardly.

ment of the fallers or of the sliver S entering or passing through the machine.

Furthermore, ample room is available at this point for mounting the brush without disturbing the normal setting of any other part of the machine. This position of the brush also permits the fallers to continue their travel to points very closely adjacent to the back or delivery rolls 15. I thus avoid the serious disadvantage of increasing the space between the fallers and the delivery rolls, and I permit the machine to operate on material of very short staple.

In actual operation, my invention has been found entirely satisfactory and effective for the purposes indicated and has been found to keep the lower fallers and needles entirely clear of dirt and waste material during long continued operation, thus avoiding the lost time previously occasioned by frequent cleaning of the lower fallers.

I have not applied my invention to the cleaning of the upper fallers, as dirt thus removed would fall on the sliver and would be seriously objectionable. Furthermore, dirt and waste material accumulates very slowly on the upper fallers and these fallers are substantially less numerous than the lower fallers. They are also readily accessible, so that occasional cleaning of the upper fallers may be accomplished quickly and easily and with slight loss of time.

While I have shown my invention applied to an intersecting gill-box having upper and lower fallers, it will be understood that the invention is equally applicable to the type of gill-box in which the upper fallers 12 are omitted and a single set of lower fallers only is used.

While I have shown a fixed bristle brush in the drawing, the particular type of brush may be varied and the brush may be either fixed or rotary, provided the working position of the brush at the feeding end of the machine is maintained.

Having thus described my invention and the advantages thereof, I do not wish to be limited to the details herein disclosed, otherwise than as set forth in the claim, but what I claim is:—

A gill-box having, in combination, a plurality of fallers having faller pins and successively movable from an initial working position along a substantially rectangular closed path having an upper working portion and a lower return portion, and a brush to clean said fallers, said brush being held fixed in position adjacent the path of upward return movement of said fallers and being successively and directly engaged by said fallers closely adjacent said pins as said fallers are moving upward to initial working position at the feeding end of the machine.

HARRY WHITAKER. 30
